OF STUTTGART, GERMANY.

SWITCH FOR LIGHTING INSTALLATIONS.

1,164,727.

Specification of Letters Patent. Patented Dec. 21, 1915.

Application filed July 1, 1915. Serial No. 37,540.

To all whom it may concern:

Be it known that I, FRANZ KRATZ, engineer, a subject of the German Emperor, residing at 59^a Schloss-strasse, Stuttgart, Germany, have invented certain new and useful Improvements in and Connected with Switches for Lighting Installations; and I do hereby declare the following to be a full, clear, and exact description of the invention, such as will enable others skilled in the art to which it appertains to make and use the same.

The invention relates to lighting installations, particularly for vehicles, in which, by means of a switch, one or more sources of current, or sets of lamps, can be connected with or disconnected from the lighting leads. By an unintentional manipulation of this switch it may happen that the lighting is suddenly extinguished. For example, if in an automobile at full speed the lamp switch or the switch for connecting the source of current is unintentionally placed in the off position, an accident is almost unavoidable in consequence of the sudden extinction of the lamps. Also, the lights may be accidentally extinguished if the switch is unintentionally turned from the position for dynamo lighting to that for battery lighting, at a time when the battery is insufficiently charged.

It is already known to provide against an unauthorized and unintended adjustment of the switch by locking it in the different positions by hand. Such a locking device affords, however, only a very limited protection, for it requires, just as much as the setting itself of the switch, the full attention of the person looking after the lighting installation. If he forgets to insert the bolt, the danger alluded to still exists.

The invention is designed to overcome this drawback.

It consists in providing a locking device of known kind which automatically holds the switch locked in one or more of the positions, in such a manner, that this locking can only be released by a particular hand lever. The switch is, therefore, permanently locked and its setting can only be altered by releasing the automatic locking device. These two manipulations necessary before the switch is set in another position, prevent any unintentional or accidental use of the switch, since the locking lever can

only be released when the switch lever is in the required position, and consequently the switch must be brought into the right setting.

In the accompanying drawing, Figures 1-3 represent diagrammatically examples of construction according to the invention.

In Figs. 1 and 3, *a* represents a shunt dynamo, *c* a battery, *e* the lamp circuit, and *f* a hand switch which can be adjusted by means of a hand lever *g*. The battery is connected with contacts 5 and 6; the dynamo machine with the contact 7 of the switch. The dotted lines show the different positions of the switch, in the position DB the battery and the dynamo are connected in parallel to the lamp leads. In the position D, only the dynamo; in the position B, only the battery is connected with the lighting leads. In the off position, both sources of current are cut off. Stops 23 and 24 limit the movement of the switch lever in the positions DB and O. In the construction shown in Fig. 1, the unearthing lighting main *e* is connected by a lead *h* with the metallic part of the switch lever *f*. A disk *i* is keyed on the spindle of the switch and is provided with four notches *db*, *d*, *b* and *O*. A catch *k* engages in these notches and is pressed by a spring *l* constantly against a stop *m*. The catch has a keyhole and can be drawn out of the notches against the action of the spring by means of the key *n*, which is shown dotted in the figure.

The device acts as follows:—The spring *l* draws the catch *k* constantly into the horizontal position, so that it always engages with one of the notches and locks the switch lever *f*, *g*. Fig. 1 shows the switch locked in the position DB. If the switch is to be brought into the position D, the key is turned in the direction shown by the arrow, thereby releasing the disk *i* while the key is held against the action of the spring until the switch is brought into the desired position, which is indicated by the easy snap of the switch into a notch, which is not shown. The key is held until this position is attained, so that the catch *k* snaps into the notch *d* and again locks the switch lever. Since the driver is compelled in this way to hold the locking device out of engagement against the tension of the spring, any unintentional setting of the switch is practically excluded.

The device described is of particular importance for the off position of the switch.

Fig. 2 shows a construction of the switch *i* in which the notches *db*, *d* and *b* are replaced by a single recess *p*. A notch *o* provided for the off position is separated from these by a projection *q*. In this form of construction the switch is not locked in the positions DB, D and B, but only lightly held in its setting by a notch, not shown. If the switch is to be set in the off position, the projection *q* opposes the locking by the catch *h* and this must be removed from the path of the disk *i* by the key before the switch can be brought into the off position.

The spring *l* shown in Figs. 1 and 2 may be replaced by a watch spring.

Fig. 3 shows a construction in which both the switch for the sources of current and also the lamp switch by which the separate lamps are connected up and disconnected, can be locked by means of the same locking device. The switch *f*, *g* for the source of current is similar to that shown in Fig. 1. The lamp switch is provided with two arms *r*₁ and *r*₂ which are connected by a web *s* and a metal spring *u* at the hand lever *t* in every position of the switch makes contact with a fixed plate *v* which is connected by a lead *h* to the switch *f*. The head lights 8 and 9 of the automobile are connected to a contact 10, the side lights 11 and 12 to a contact 13. In the position I of the switch only the side lights, in the position II the side and head lights, in the position III only the head lights are supplied with current. In the off position all the lamps are cut out. Stops 23' and 24' limit the movement of the switch lever in the extreme positions I and O. On the spindle of the switch lever *f* there is a disk *i*, in which a long recess *p* is cut off by a stop *q* from a short recess *o*. Symmetrical thereto in the corresponding disk *i'* of the lamp switch *r*₁, *r*₂ there are a large notch *p*₁, a stop *q*₁ and a small notch *o*₁. A stirrup piece 14 is provided with teeth 15 and 16, which ordinarily engage in the recesses of the disk *i* and *i'*. The stirrup 14 is carried by a sleeve 17 which is guided in a boring 18 of a fixed part 19 of the frame. A spring 20 presses the stirrup 14 against a short arm *k* rotatable about a pin 21, so that the arm is pressed against a fixed stop *m*. The arm *k* can be turned by the key *n* in the direction of the arrow shown in dotted lines, to depress the stirrup 14. A shoulder 25 of the stirrup limits its downward movement, so that the torque exerted by the spring 20 is sufficient to return the arm to its original position.

The action is as follows: In the positions DB, D and B of the switch *f*, *g* and also in the positions I, II and III of the lamp switch the movements of the disks *i*, *i'* are

allowed by the long recesses *p* and *p*₁ and are not interfered with by the teeth 15 and 16 of the stirrup 14, but as soon as either the switch *f*, *g* or the lamp switch, or both, are brought into the off position, the projection *q* or *q*₁ presses on the tooth 15 or 16 and the key *n* must be turned in the direction of the hands of a watch, in order, by the pressure of the surface 22 of the arm *k*, to depress the stirrup 14. Thereby, the teeth 15, 16 are depressed so far that the projections *q* and *q*₁ can pass unhindered over the teeth 15, 16. If now one or both of the switches are to be brought into the off position, the arm *k* is allowed to snap back, so that the teeth 15 and 16 catch in the notches *O* or *O*₁, and lock the switches. The switches can be brought to the off position either singly or together.

In the constructions shown in Figs. 1 and 2, two or more switches can be provided with the same locking device.

Having now particularly described and ascertained the nature of my said invention and in what manner the same is to be performed, I declare that what I claim is:—

1. In an electric switch, the combination of a series of fixed contacts, a switch member movable over said contacts to make engagement therewith successively and movable to a position at one side of the series of contacts constituting the open position of the switch, a locking member movable with the switch member and having a plurality of notches, a catch device normally held in operative position to engage in one or the other of said notches, said catch device and notches being designed to permit movement of the switch member in at least one direction over the series of contacts but being designed to prevent movement of the switch member to its open position, and manually actuated means to withdraw the catch device temporarily from its normally operative position.

2. In an electric switch, the combination of a series of fixed contacts, a rotatable switch member movable over said contacts to make engagement therewith successively and movable to a position at one side of the series of contacts constituting the open position of the switch, a disk secured to the switch member and rotatable therewith and having a plurality of notches formed in its periphery, a spring-pressed catch device normally held in operative position to engage in one or the other of said notches, said catch device and notches being designed to permit movement of the switch member in at least one direction over the series of contacts but being designed to prevent movement of the switch member to its open position, and manually actuated means to withdraw the catch device temporarily from its normally operative position.

3. In an electric switch, a plurality of sets of fixed contacts, a switch member associated with each of the sets and movable into and out of engagement with the contacts 5 thereof, an electrical connection between the switch members, each switch member being provided with a locking member movable therewith and having a plurality of notches, a catch normally held in operative position 10 to engage the notches of the locking mem- bers, and manually actuated means to withdraw the catch temporarily from its normally operative position.
- In testimony wherof I have affixed my signature, in presence of two witnesses.

FRANZ KRATZ.
